DESCRIPTION

FIG. 1 is a first perspective view of the electrical connector in accordance with a first embodiment of our new design;

FIG. 2 is a second perspective view of the electrical connector illustrated in FIG. 1;

FIG. 3 is a front elevational view of the electrical connector illustrated in FIGS. 1 and 2;

FIG. 4 is a back elevational view of the electrical connector illustrated in FIGS. 1-3;

FIG. 5 is a top end plan view of the electrical connector illustrated in FIGS. 1-4 as viewed along its longitudinal axis in FIG. 3;

FIG. 6 is a bottom end plan view of the electrical connector illustrated in FIGS. 1-5 as viewed along its longitudinal axis in FIG. 3;

FIG. 7 is a left side elevational view of the electrical connector illustrated in FIGS. 1-6;

FIG. 8 is a right side elevational view of the electrical connector illustrated in FIGS. 1-7;

FIG. 9 is a first perspective view of the electrical connector with locking ring removed in accordance with a second embodiment of our new design;

FIG. 10 is a second perspective view of the electrical connector with locking ring removed illustrated in FIG. 9;

FIG. 11 is a front elevational view of the electrical connector with locking ring removed illustrated in FIGS. 9 and 10;

FIG. 12 is a back elevational view of the electrical connector with locking ring removed illustrated in FIGS. 9-12;

FIG. 13 is a top end plan view of the electrical connector with locking ring removed illustrated in FIGS. 9-12 as viewed along its longitudinal axis in FIG. 11;

FIG. 14 is a bottom end plan view of the electrical connector with locking ring removed illustrated in FIGS. 9-13 as viewed along its longitudinal axis in FIG. 11;

FIG. 15 is a left side elevational view of the electrical connector with locking ring removed illustrated in FIGS. 9-13; and,

FIG. 16 is a right side elevational view of the electrical connector with locking ring removed illustrated in FIGS. 9-14.
